(57) **CLAIM**

The ornamental design for a tray for packaging of food products as shown and described.

DESCRIPTION

The file of this patent contains at least one drawing/photograph executed in color. Copies of this patent with color drawing(s)/photograph(s) will be provided by the Office upon request and payment of the necessary fee.

1. Tray for packaging of food products

2. Tray for packaging of food products

3. Tray for packaging of food products

1.1 is a perspective view of a tray for packaging of food products, showing my new design in an open condition with the inner part being removed;

1.2 is a perspective view thereof, in a closed condition showing the inner part attached;

1.3 is another perspective view thereof, in a closed condition with the inner part being removed;

1.4 is a top view thereof showing the inner part attached;

1.5 is a top view thereof, in an open condition, showing the inner part detached; and

1.6 is a perspective view thereof in a closed condition showing the inner part attached.

**1 Claim, 6 Drawing Sheets
(6 of 6 Drawing Sheet(s) Filed in Color)**
